UNITED STATES PATENT OFFICE

GEORGE M. BICKNELL, OF ST. LOUIS, MISSOURI, ASSIGNOR TO CARTER CARBURETOR CORPORATION, OF ST. LOUIS, MISSOURI, A CORPORATION OF DELAWARE

CARBURETOR

Original application filed March 31, 1921, Serial No. 457,247. Divided and this application filed January 19, 1927. Serial No. 162,907.

My invention relates to improvements in carburetors, and has for its primary object the construction of a carburetor that will give a very rich mixture for starting an automobile engine. A mixture that will be composed of enough air and atomized fuel to form a combustible mixture in a cold cylinder and to permit the regulating of the amount of air admitted to the mixture so that the greatest possible velocity of air will be maintained at the nozzle outlet.

A further object is to construct a carburetor of the plain tube type that will supply a very rich mixture of fuel and air when fully choked and that controls the amount of air entering the mixture chamber at the restricted opening of the Venturi tube so that the greatest air velocity when choked, or partially choked, will be maintained at the nozzle outlet into the venturi.

At the present time practically all carburetors are equipped with some device for choking or enriching the mixture for use in starting the engine to which the carburetor is attached when the engine is cold. In the case of automobile engines, these choking devices are usually connected so that they can be operated from the dash or the instrument board without the driver leaving his seat, the choking devices being used both in starting and in warming up the engine, as a mixture much richer in fuel is required when the engine is cold than is necessary or practical when the engine is thoroughly warmed up.

The majority of carburetors of the Venturi or plain tube type, that is, carburetors not using an air valve or weights in the air passage, control the amount of air entering the mixing chamber with a butterfly type choke valve in the main inlet passage. When closed this valve shuts off practically the entire supply of air entering the carburetor and when the motor is cranked for starting, a very high suction is applied to the carburetor nozzle or nozzles and fuel is drawn into the manifold or pipe connecting the carburetor with the engine cylinders. The high vacuum in the manifold assists in vaporizing the lighter and more volatile parts of fuel and, if the engine does not start promptly with

this method of choking, it is necessary to open and close the choke valve while cranking the motor thus admitting occasional drafts of air to the cylinders in order to secure a mixture of fuel and air that will form a combustible or explosive mixture as drawing fuel only into the cylinders will cause them to load up or become flooded with raw liquid fuel, and this will make starting much harder as well as thinning out the lubricant in the crank case due to this liquid fuel seeping past the piston rings, down the cylinder walls, and into the crank case.

By my construction these conditions are practically eliminated as only the main Venturi air passage is closed when the carburetor is fully choked. The secondary air passage leading from the main inlet to the carburetor well remains open at all times, and by my peculiar arrangement of choke, the highest velocity of the air entering the mixing chamber is maintained at the end of the secondary Venturi tube or nozzle so that the fuel, which passes therefrom, will be thoroughly atomized and thus slugs or gobs of raw fuel will not be drawn into the cylinders.

This application is a division of my application filed March 31st, 1921, Serial No. 457,247, which has matured into Patent No. 1,630,887 patented May 31, 1927.

In the drawings:

Fig. 1 is a side elevation of a carburetor embodying my construction;

Fig. 2 is an enlarged view of the same with parts broken away and in section;

Fig. 3 is an enlarged fragmental view of the accelerating tubes, choke valve and the lower portion of the venturi;

Fig. 4 is an enlarged cross section taken on the line 4—4 of Fig. 2;

Fig. 5 is a section taken on the line 5—5 of Fig. 4; and

Fig. 6 is a side view of the accelerating tubes employed.

In the construction of my device I employ a housing or casing 7, which has a flange 8 at its upper end by means of which the carburetor is attached to the intake manifold of an internal combustion engine.

Integral with the casing 7 is a float cham-

ber 9 which is of ordinary construction and which is provided with a strainer 10 having a fitting 11 for the attachment of a fuel pipe.

5 Formed in the housing 7 is a main air inlet 15 and a mixing chamber 16. These chambers communicate with each other so that air can pass from the main air inlet into the mixing chamber. Located in the lower end 10 of the mixing chamber is a Venturi tube 17. The upper portion of the housing 7 forms the suction chamber 18. The suction chamber and mixing chamber are separated from each other by means of a throttle valve 19. This 15 throttle valve is mounted on a shaft 20 to the outer end of which is secured a lever 21. Secured to the lever 21 is a rod or cable 22, which leads to the throttle control located at any suitable point.

20 Secured in the main air inlet and concentric with the opening in the Venturi tube 17 is a well 23. This well communicates with the float chamber 9 by means of a passage 24 so that fuel can be supplied to the well. The 25 amount of fuel, or rather its rate of supply to the well, is controlled by means of a needle valve 25.

Extending upward from the passage 24 is a passage 26, which communicates with a 30 port 27, forming the passage for the idling mixture which supplies fuel to keep the engine turning when the throttle valve is closed to its idling position.

Carried by the upper end of the well 23 is 35 the secondary Venturi tube or nozzle 28, its lower end being provided with a screw threaded cross 29 thus forming passageways 30 through which air can enter the well.

Secured to the underside of the cross 29 is 40 a bar 31 which has extending therethrough accelerating tubes 32, 33 and 34. As will be noted from Figs. 2, 5 and 6, these tubes all terminate in the same plane above the bar 31 but extend to various depths in the well. 45 It will also be noted that the tubes extend into the secondary Venturi tube 28.

Surrounding the well and secondary Venturi tube is the choke valve 35, its upper end 50 converging toward the tube as indicated by the numeral 36. This converging part is preferably conical as a finer adjustment can be obtained by this shape although, if found desirable, I may vary the shape of the upper end.

55 Integral with the converging portion 36 is a downwardly extending sleeve 37. This sleeve fits snugly around the outer portion of the secondary Venturi tube but is not tight enough to bind thereon so that the choke 60 valve can be freely moved up and down. It will be noted from Figs. 2, 3 and 6 that the inside diameter of the valve 35 is larger than the well 23 so as to form a passageway 38 completely around the well. This permits air 65 to pass upward through the passageway 38,

down through the passages 30 into the well and out through the secondary Venturi tube 28.

Extending through the air inlet 15 is a shaft 39 on which is mounted a gear wheel or pinion 40. This pinion meshes with teeth 41 cut on the choke valve 35. Secured to the outer end of the shaft 39 is a lever 42 to which is attached a rod or cable 43 by means of which the choke valve can be raised and lowered. This rod also extends to a suitable place for operation, the same as the rod 22.

The operation of my device is as follows: After the carburetor has been properly installed and adjusted when it is desired to start the engine, the throttle valve 19 is slightly open and the choke valve 35 is closed. By moving the lever 42 so that the upper portion 36 of the choke valve will contact with the Venturi tube 17 air is prevented from passing directly from the main air inlet into the venturi.

The suction caused by cranking the engine immediately starts a flow of fuel and air through the second Venturi tube 28, the air entering the well through the passages 38 and 30 as shown in Fig. 5. These passages remain open at all times. This air mixes with the fuel which is drawn from the well through the accelerating tubes 31, 32 and 33 causing a spray of fuel and air to pass through the mixing chamber into the manifold and cylinders. It will be noted that even when the carburetor is fully choked a mixture of fuel and air will always be drawn from the carburetor in the form of a mist and that it will be impossible to draw liquid fuel only into the intake manifold. As the engine warms up the choke valve 36 is gradually lowered until when the engine is thoroughly warmed, the valve is in its lowest or regular running position. As the valve is lowered, the upper end 36 of the choke valve gradually leaves the reduced portion of the Venturi tube 17 permitting air to pass from the main air inlet 15 between the reduced portion of the Venturi tube and the tapered portion of the choke valve. This air will pass upward and around the upper portion of the choke valve in such a manner that its highest point of velocity is near the upper end of the choke valve.

The operation of the accelerating tubes is as follows: When not in action the fuel level in the carburetor well will be near the upper ends of the accelerating tubes. When the engine is idling this level will be slightly lowered by the flow of fuel through the idling tube. As soon as the throttle is opened causing enough suction to be applied to the accelerating tubes to lift fuel therefrom, the level in the well will be further lowered until it reaches the lower end of the tube 32. Air will then be admitted, which unites with the fuel causing a spray of fuel and air to be de-

livered into the secondary venturi from the top of this tube. A greater throttle opening will further lower the fuel level in the well causing similar action to take place in the tubes 33 and 34, that is, they first deliver fuel only into the secondary venturi, then a spray of fuel and air. In this manner a rich accelerating mixture is secured when the throttle is first opened as the air, which enters the well through the passages 38 and 30 and is drawn into the secondary venturi 28, passes the upper ends of the accelerating tubes and assists in raising the fuel in the well through these tubes and in breaking this fuel up into fine particles in which state it can be easily carried by the air stream into the cylinder. When the throttle is closed and only the idle jet in action fuel flowing past the needle valve 25 rapidly refills the well.

In the ordinary type of carburetors where the choke valve is in the main air inlet, the highest point of velocity was around the choke valve and not around the nozzle. This permitted slugs or gobs of liquid fuel to be drawn up, which were too heavy to be carried into the cylinder and, consequently, settled on the sides of the manifold and ran down, and if several gobs or slugs of raw fuel in succession found their way into a cylinder, that cylinder would become, what is termed, "flooded". In other words, there was more fuel in the cylinder than could be properly ignited and consequently it was impossible to start the engine until this fuel had evaporated or drained from the cylinder in sufficient quantity to permit an explosive mixture to be formed when the engine was again cranked.

By my construction of carburetor the fuel as it issues from the main nozzle is thoroughly atomized so that what may be termed a "wet gas" is delivered to the cylinder when the choke is fully closed but no gobs or slugs of fuel will be delivered, because the high velocity of the air at the discharge or upper end of the secondary venturi is sufficient to break the slugs or gobs up and atomize them so that there will be no danger of flooding the cylinders.

It will also be noted that when the choke valve, in my structure, is fully closed there is always a certain amount of air admitted, which will mix with and atomize the fuel because of my construction the entire suction is not placed on the fuel supply as is the case where a butterfly valve is used in the main air inlet. Consequently there is very little danger of choking or flooding the engine with raw fuel when the choke is fully pulled out or closed, and furthermore by my construction as the choke valve is gradually opened, the greatest suction possible created by the velocity of the air passing through the Venturi tube is at the discharge end of the secondary venturi and not around the edges of

the valve as is the case where a butterfly valve is used in the main inlet.

While I have shown my device as employing a plurality of accelerating tubes, I do not desire to limit myself thereto as a single nozzle may be employed without departing from the spirit of my invention.

It will also be noted from my construction that the passageway 38, the passages 30, and the main fuel nozzle 28 constitute what may be termed an "auxiliary air passage", which communicates with the main passage 15.

Having fully described my invention, what I claim is:—

1. A carburetor comprising a casing having a main air passage therein, a mixing chamber communicating with said main air passage, a Venturi tube located in the mixing chamber, a nozzle for supplying both fuel and air carried by said casing and terminating near the point of greatest constriction in the Venturi tube, a manually operated means having a conical upper end whereby the passage of air from the main air passage through said point of greatest constriction can be regulated and maintained constant for a predetermined length of time whereby the highest velocity of air passing from said main air inlet to the mixing chamber is maintained adjacent the end of the nozzle, and a throttle valve located above said Venturi tube.

2. A carburetor comprising a casing having a main air passage therein, a mixing chamber communicating with said main air passage, a Venturi tube located in the mixing chamber, a throttle valve located beyond the delivery end of said Venturi tube, a secondary Venturi tube for supplying both fuel and air carried by said casing and terminating near the point of greatest constriction in the Venturi tube, and manually operated means whereby the passage of air from the main air passage through said point of greatest constriction can be fixed and regulated so that the highest velocity of air passing from said main air inlet to the mixing chamber is maintained adjacent the end of the secondary Venturi tube without varying the amount of fuel normally delivered to said second venturi.

3. A carburetor comprising a casing having a main air chamber, a mixing chamber in said casing communicating with said main air passage, a Venturi tube located within said mixing chamber, a well carried by said casing, means for predetermined the delivery of fuel to said well a secondary Venturi tube carried by said well, the upper end of said secondary Venturi tube terminating adjacent the point of greatest constriction in the first mentioned Venturi tube, a choke valve having a conical upper end surrounding said secondary Venturi tube, means manually operated for raising and lowering and retain-

ing said choke valve in predetermined position, the conical end of said valve adapted to enter the first mentioned Venturi tube for regulating its communication with the main air passage without obstructing the flow of air whereby the highest velocity of air passing into the mixing chamber is maintained at the point of fuel delivery therein, and a throttle valve for controlling the passage of air and fuel from said mixing chamber.

4. A carburetor comprising a casing having a main air passage, a mixing chamber communicating therewith, a Venturi tube located in said mixing chamber, a well carried by said casing, means for feeding a constant amount of fuel to said well, a nozzle carried by said well and having its upper end terminating adjacent the point of greatest constriction of the Venturi tube, a conical choke valve surrounding said nozzle, manually operated means for raising and lowering and retaining said choke valve in position, the upper end of said choke valve being adapted to enter the Venturi tube for opening and closing its communication with the main air inlet whereby the highest velocity of air passing into the mixing chamber is maintained at the point of fuel delivery therein, and a valve for controlling the amount of air and fuel drawn from said mixing chamber.

5. In a carburetor a main air passage, a mixing chamber, a throttle valve in said mixing chamber, a Venturi tube below said throttle valve for connecting the main air passage to the mixing chamber, a well below said Venturi tube, an auxiliary passage including a second Venturi tube communicating with the well and first mentioned Venturi tube and arranged to convey air downwardly into said well and upwardly in said second Venturi tube, and means surrounding said second Venturi tube for closing and regulating the size of the opening in the first mentioned Venturi tube without changing the size of the auxiliary passage.

6. A carburetor comprising a housing, a main air passage formed in said housing, an auxiliary passage communicating with said main air passage, means including a fuel well having an air vent and a plurality of vertically spaced discharge outlets for feeding a mixture of air and fuel through said auxiliary passage to said main air passage, manually operated means for controlling the capacity of the main air passage, said means being stream lined to provide a gradual increase and decrease of air velocity, the point of communication of said auxiliary passage with said main passage being substantially at the point of highest velocity of the air flowing through said passage.

7. A carburetor comprising a housing, a main air passage formed in said housing, a throttle valve and a choke valve in said pas-

sage, a venturi in said passage adjacent said choke valve, means including a fuel well having an air vent and a plurality of vertically spaced discharge outlets for discharging a mixture of air and fuel into said main air passage way near its most restricted portion, said choke valve being stream lined to cause a gradual change in the velocity of the air and being constructed and arranged to direct an air current at high velocity directly past the discharge outlet of the fuel supply means.

8. In a carburetor, a fuel mixing conduit comprising a main passageway having an inlet and an outlet, a throttle valve controlling said outlet, a venturi formed in said passageway, a fuel chamber, an auxiliary passageway adapted to receive fuel from said chamber, said chamber having an air vent near the upper part thereof, means comprising a constant level supply chamber and a calibrated passage way for supplying fuel to said fuel chamber, a second venturi in said auxiliary passageway, said second venturi having an air inlet and a discharge outlet substantially concentric with first-named venturi and terminating at the throat thereof, and a manually operable choke valve slidably mounted in concentric relation with the first-named venturi and surrounding the discharge outlet of the second venturi.

9. In a carburetor, a fuel mixing conduit comprising a main passageway having an inlet and an outlet, a throttle valve controlling said outlet, a venturi formed in said passageway to gradually increase and decrease the velocity of the fluid passing therethrough, a fuel chamber, an auxiliary passageway adapted to receive fuel from said chamber, a venturi in said passageway, a plurality of vertically spaced air inlets for said venturi, said venturi having a discharge outlet substantially concentric with said first-named venturi and terminating at the throat thereof, and a manually operable choke valve slidably mounted in concentric relation with the first-named venturi and surrounding the discharge outlet of the second venturi, said choke valve tapering inwardly and toward the discharge outlet of the auxiliary venturi whereby a fluid stream is directed toward said auxiliary discharge outlet at high velocity.

10. In a carburetor, a fuel mixing conduit comprising a main air passageway having a venturi therein, an auxiliary air and fuel passageway concentric with said venturi and discharging substantially at the throat thereof, a choke valve slidably mounted on said auxiliary conduit, said choke valve having a tapered end for regulating or closing the venturi, the inner wall of said choke valve being adapted to extend beyond the end of the auxiliary passageway when the choke valve is closed, and the outer wall of said choke valve being adapted to direct a stream of air at high velocity into contact with the air.

and fluid discharged from the auxiliary passageway.

11. In a carburetor, means for forming an emulsion of liquid fuel and air; said emulsion forming means comprising a fuel well having an air vent, one or more discharge outlets, at least one of said outlets being below the normal liquid fuel level, and a calibrated fuel inlet, means including a venturi for mixing additional air with the emulsion to form a spray of liquid fuel and air; means comprising a venturi for mixing additional air with said spray to produce a final mixture; and means for varying the velocity of the air mixed with said spray at the mixing point.

12. In a carburetor, means for forming an emulsion of liquid fuel and air; said emulsion forming means comprising a fuel well having an air vent, one or more discharge outlets, at least one of said outlets being below the normal liquid fuel level, and a calibrated fuel inlet; means including a venturi for mixing additional air with the emulsion to form a spray of liquid fuel and air; means comprising a venturi for mixing additional air with said spray to produce a final mixture; and means for varying the velocity of the air mixed with said spray at the mixing point; and means posterior to said mixing point for controlling the flow of mixture through the carburetor.

13. In a carburetor, means for forming an emulsion of liquid and air; said emulsion forming means comprising a fuel well having an air vent, one or more discharge outlets, at least one of said outlets being below the normal liquid fuel level, and a calibrated fuel inlet; means for mixing additional air with said emulsion to produce a final mixture; means for varying the velocity of the air mixed with said emulsion at the mixing point; and means posterior to said mixing point for controlling the flow of mixture through the carburetor; said flow control means comprising a butterfly throttle; a low speed fuel supply conduit discharging adjacent the edge of said butterfly throttle, said low speed fuel conduit and said well being supplied with fuel through a common calibrated passageway; said passageway tending to restrict said fuel supply, whereby the operation of either the well or the low speed fuel supply will tend to restrict the discharge of fuel from the other.

55. In testimony whereof I have affixed my signature.

GEORGE M. BICKNELL.
